United States Patent Office.

MARCIA ADKINS, OF OSWEGO, NEW YORK.

Letters Patent No. 92,926, dated July 27, 1869.

IMPROVEMENT IN HAIR-CURLING APPARATUS.

The Schedule referred to in these Letters Patent and making part of the same.

To all whom it may concern:

Be it known that I, Mrs. MARCIA ADKINS, of Oswego, in the county of Oswego, and State of New York, have invented a new and improved Hair-Curling Apparatus; and I do hereby declare that the following is a full, clear, and exact description thereof, which will enable others skilled in the art to make and use the same, reference being had to the accompanying drawing, forming part of this specification.

This invention relates to improvements in hair-curling implements.

It consists in the application, to a hollow heating and curling-mandrel, of a combing, pressing, and spirally-laying apparatus, as hereinafter more fully specified.

Figure 1 represents an elevation, partly sectioned, of my improved device.

Figure 2 represents a transverse section, taken on the line $x-x$ of fig. 1.

Similar letters of reference indicate corresponding parts.

A represents a hollow tapered heating and winding-mandrel, through the handle of which, at B, the heating-iron is inserted.

C represents a helical band of metal, the bore of which is considerably larger than the mandrel whereon the hair is to be laid.

This coiled band carries at one end a spring-pad, D, of any suitable smoothing-substance, and a comb, E, the teeth of which stand radially from the centre.

F represents a guide-pin, connected to the mandrel near the small end, but removable therefrom.

For curling a bunch of hair, the spiral band is adjusted on the mandrel with the comb and spring-pad, near the pin F. The bunch of hair is tied to the latter, passed under the spring-pad, and through the comb.

The spiral band is then turned to the right, screwing on to the mandrel, drawing the hair through the comb under the brush, and laying it in regular spiral coils on the mandrel, which, being heated, forms the hair (which is allowed to remain a sufficient length of time on the mandrel) into the desired curl. The latter is removed by withdrawing the pin, slipping off the spiral band, and then the curl.

In this way the curls may be very rapidly and perfectly formed.

Having thus described my invention,

What I claim as new, and desire to secure by Letters Patent, is—

The combination, with the heating and winding-mandrel A, of the spiral band C, spring-pad D, comb E, and guide-pin F, substantially as specified.

The above specification of my invention signed by me, this 19th day of April, 1869.

MRS. MARCIA ADKINS.
